SETTING-LOCK FOR TIME-FUSES.

1,358,236.

Specification of Letters Patent.

Patented Nov. 9, 1920.

Application filed January 5, 1918. Serial No. 210,494.

To all whom it may concern:

Be it known that I, OLOF OHLSON, a citizen of the United States, residing at Newton, in the county of Middlesex and State of Massachusetts, have invented new and useful Improvements in Setting-Locks for Time-Fuses, of which the following is a specification.

This invention relates to time fuses adapted to detonate explosive charges, and particularly to fuses which are applied to artillery shells for the purpose of exploding the shell after lapse of a given time following the firing of the shell from a gun. Such fuses are equipped with adjustable timing devices, by the setting of which the time of detonating the shell is determined.

The particular object of my invention is to provide, in connection with a means for setting the timing device of such a fuse, a proper locking means for securing the setting means and the timing device in such manner that the adjustment of the latter will not be disturbed or altered by the shocks to which the fuse is subjected when the shell to which it is applied is fired from the gun. A further object is to associate with such lock and setting means, complementary stops for use when the fuse to which the invention is applied is of the mechanical type wherein the detonation is effected by hammer and trigger mechanism to impose limits to the adjustment of the timing device at such points that, on the one hand accidental release or operation of the hammer and trigger mechanism is prevented, and on the other hand injury to such mechanism is prevented.

The invention consists in means for accomplishing the foregoing objects in the manner hereinafter set forth, and includes not only the specific embodiment illustrated and described in the following specification, but also all modifications of the same containing the essential principles thereof embraced within the scope of the appended claims. The particular form of the invention here shown is designed for application to mechanical fuses of the sort disclosed in my applications for Letters Patent of the United States No. 206,278 filed December 8, 1917, and No. 170,421 filed May 23, 1917, but the essential principles are not limited to the combination with or application to that particular fuse, or even to a fuse of the me-

chanical type as distinguished from those of other types, wherefore my claim to protection is not limited otherwise than appears from the express terms of the appended claims.

Referring to the drawings,

Figure 1 shows in elevation a time fuse having my invention applied thereto.

Fig. 2 is a sectional view on line 2—2 of Fig. 1 and a plan view of the parts below said line.

Fig. 3 is a plan view as seen from beneath 65 of the setting member and lock in which my invention is contained.

Fig. 4 is a plan view of the base showing the same with all superposed parts removed.

Fig. 5 is a longitudinal section on a larger 70 scale of those parts of the fuse which include my invention and the essential coöperating parts.

Fig. 6 is a perspective view in detail of the lock.

The same reference characters indicate the 75 same parts in all the figures.

10 is the base of the fuse, 11 the setting member or means, 12 the cap and 13 the timing device which is adjustable to determine 80 the time of detonation of the shell to which the fuse is applied, and is engageable with the setting member through a coupling 14. The base is provided with a screw threaded shank 15 adapted to be screwed into a 85 threaded hole in the nose of a shell, but any other suitable means for attaching it to the shell may be provided. As the fuse here shown is of the mechanical type, the base is provided with a chamber 16 shown in Fig. 4 90 to receive a percussion cap which is adapted to be ignited by a mechanically actuated hammer which is controlled by the timing device 13.

Both the timing device 13 and the setting 95 member 11 are mounted in such a manner as to be rotatable about the same axis, which is the geometrical axis of the fuse, and coincides as nearly as possible with the axis about which the shell rotates when in flight. The 100 setting member is a ring which surrounds the timing device and also the fuse mechanism, and is connected to the fuse base by means which permits its rotation and at the same time prevents it from being removed 105 from the base, such means being preferably overlapping annular ribs 17 and 18 on the

base and setting member respectively, and a locking wire 19 seated in complementary registering grooves in said annular ribs.

In the type of fuse so illustrated the timing device 13 is driven rotatably by mechanism and it causes or permits release of a firing pin or hammer when a notch 20 in the rim of said device (see Fig. 2) arrives beside an upstanding finger 23 which crosses the plane of said rim and is carried by a lever 24, said finger being shown in Figs. 2 and 5. At such time the finger 23, which is constantly pressed toward the timing device and always bears on the rim thereof, enters the notch 21 and causes release of the hammer, which is then actuated to ignite the percussion cap and so fire or detonate the explosive charge in the shell. Although the end of finger 23 overhangs the edge of the timing device, as shown in Figs. 2 and 5, the upstanding part of the finger does not enter any part of such edge, which is continuous and without indentations of any sort, except the notches 21 and 28, until it enters notch 21, as above described. The instant when this action occurs is called for the purposes of the present description, the time of detonation of the fuse. The hammer and trigger mechanism which is controlled by the timing device 13 and by the release lever 24, is not here shown for the reason that it is not material to the present invention what the precise nature of such mechanism may be, but for a complete illustration of an operative mechanism adapted to be used with the devices here shown, attention is directed to my pending application Serial Number 206,278 hereinbefore referred to. For the purposes of this specification, the lever 24, or its finger 23 may be called a tripping device for tripping, that is, permitting operation of, the firing hammer and so detonating the exploding charge, when the timing device arrives in a certain position.

The coupling 14 is a spring arm secured at one end by screws 25 to the interior surface 27 of the setting ring, and having its opposite end bent toward the timing device and arranged so that it may enter a notch 28 in the rim of the latter near the notch 21, and beside a projection 29. Said coupling is thus engaged with the timing device, so that the latter may be moved in either direction by corresponding movements of the setting member 11, at any time before the shell is to be fired, and it may then be withdrawn from this notch, to permit driving of the setting device by the mechanism provided for the purpose in the direction indicated by the arrow in Fig. 2. This coupling may be actuated in the manner indicated by means such as that disclosed in my pending application Serial Number 170,421 previously referred to, or by any other means suitable for the purpose. Even when thus withdrawn

from the notch 28, the coupling still remains within the zone of the projection 29 so as to act as an abutment to the projection to prevent relative backward rotation of the timing device by its inertia when the shell is suddenly set into rotation by the rifling of the gun upon firing.

The explosion of the charge which propels the shell applies a sudden and violent impact to the shell and the rifling of the gun causes it to start rotating with almost equal violence. The inertia of the setting member or ring 11 and of the cap 12, which is mounted upon said ring, would cause the latter to turn rearwardly with respect to the base, which is rigidly attached to the shell, in the absence of any locking means to prevent such relative motion. I have provided locking means to prevent this action, which embodies the principal novel features of the present invention. Such locking means comprises wedges 30 and 30^a, here shown as three in number which are connected together by a band 31. These wedges and the band fit loosely within the setting ring and are surrounded by the surface 32 of the latter. The ends of the wedges project into recesses or sockets 33 and 33^a in the base. The external surfaces of these wedges are parallel with the fuse axis, but their interior surfaces are inclined to such axis, and are tapered toward the ends which enter the sockets 33. Normally the wedges loosely engage the base and the setting member and offer no appreciable resistance to the free movement of the latter, but under the impact applied by the explosion of the propelling charge, their inertia, supplemented by the inertia of the band 31, drives them forcibly into the recesses 33 and wedges them between the parts of the base and of the setting member against which their inner and outer surfaces respectively bear. The band 31 is sufficiently flexible as not to prevent them from being crowded outward against the setting member by this wedging action. Thus the wedges are set back upon firing the gun so as to lock the setting member in the adjustment which has been given, and enable the latter to hold the timing device against relative backward rotation when the shell begins to spin.

The band 31 serves a three fold purpose. First, to hold the wedges in position so that they will point in the direction in which they are driven by set back as above described; second, to load the wedges with additional weight the inertia of which augments the force of set back; and, third, to carry a stop presently to be described. Of itself the band has no locking function, but such function is served wholly by the wedges. And so far as this function is concerned it is not necessary that there be more than one wedge. It is preferable, however,

to provide a number of wedges in order to distribute the locking effect and thus secure the setting member more firmly.

The third function of the band 31, above referred to, will now be described. This band carries at any convenient point a stop constituted by two short inwardly projecting pins or studs 34, said stop coöoperating with a complementary stop 35 in the form of a pin carried by a part of the setting member and projecting downwardly inside the band 31 and at a greater distance from the axis of the fuse than the inner end of the stop pins 34. The purpose of the complementary stops 34 and 35 is to apply limits to the possible movement of the setting member so that the latter can not turn through a complete rotation. By referring to Fig. 2 it will be noted that the timing of the fuse is effected by turning the setting device to enlarge or restrict the angle, in the direction of the arrow, from the notch 28 to the finger 23. If by adjustment of the timing device the notch should be brought all the way to the finger, the latter would enter it and the hammer and trigger mechanism would be tripped. This would leave the hammer resting on the centrifugal safety guard, with which the particular fuse here shown is equipped, instead of on the trigger, and prevent the proper functioning of the hammer after the shell is fired from the gun. Hence the stop 34 is so placed as to arrest the setting member at a point short of the point where the notch 21 is brought into exact registry with the finger 23.

The opposite side of the stop is located to arrest the rotation of the setting member in the direction opposite to that above indicated before the coupling has quite reached the finger 23, in order to avoid any injury to such finger, or to the lever 24 by which it is carried, by jamming of the coupling forcibly against the finger. Thus the total range of adjustment permitted is less than a complete rotation of the setting member by the angle subtended by the combined width of the stops 34 and 35.

In this discussion the stop 34 has been treated as a single unit because in effect it is exactly that, in spite of the fact that it is composed of two structurally distinct pins or studs. Provided the stop is so designed and located as to limit the adjustment of the setting member in the manner above described, it is immaterial what its construction in detail may be and whether it is made as a single piece or of a number of pieces.

In order to insure that in assembling the parts of the fuse the stops last described will be properly positioned with respect to the finger 23 and the notch 21 and coupling 14, the structural element consisting of the band and wedges is so made that it can be placed in only one position, and to

that end one of the wedges, designated 30^a, and the socket 33^a in which it is received, are made wider than the other wedges and sockets. The same result is obtainable by making one of the wedges and its complementary socket narrower than the others, or thicker or thinner in the radial direction, or otherwise of a different form from the other wedges and sockets, or by spacing the wedges and sockets unequally. The essential point of this part of the invention is that the wedges are inseparably connected to the band and are adapted to enter sockets, and that one of the wedges and its complementary socket are different in dimensions or form from the other wedges and sockets, or there is such irregularity in spacing that the wedges can be entered in their sockets only when the band is in a specific position with relation to the other parts of the fuse. Unless the wedges are entered in the sockets, the setting member can not be seated on the base so as either to engage the coupling with the timing device, or to receive the locking wire 19; because an internal shoulder 36 is provided on the setting member which overlies and engages the upper edge of the band 31. If the points of the wedges bear on the base without entering the sockets, the band holds the setting member in a position where it is totally inoperative.

The cap 12 is preferably of metal having sufficient strength to protect the mechanism of the fuse from injury in case the shell should be accidentally dropped with its point downward; and it is also preferably of finely tapered form to diminish the air resistance. Structurally it is a separate piece from the setting member, and it may be applied thereto in a variety of ways, either by screws 37 as shown in Fig. 1, which pass through the base of the cap into that part of the setting member which is surrounded by the cap, or by virtue of the construction shown in Fig. 5 wherein the setting member and the base portion of the cap are provided with interlocking shoulders 38 and 39, respectively. Owing to the tapered formation of the setting member the cap may be forced over it by the application of sufficient force, the metal of the cap stretching within the elastic limit enough to permit the shoulder 39 to pass over the shoulder 38 and then to spring into place below the latter. This forms a connection preventing accidental removal of the cap and also making impossible intentional mischievous removal of the same for the purpose of tampering with the fuse mechanism.

The essential principles of this invention are adaptable to time fuses of other types than the mechanical type, and to other mechanical time fuses than the specific one illustrated in my prior applications herein-

before specified. I conceive that these principles may thus be combined with any fuse having a setting member operable by adjustment to effect the timing of the fuse, wherefore I do not restrict the invention for which I ask protection to the specific combination in which the same is here disclosed, or in any other manner than as appears from the express terms of the appended claims.

10. What I claim and desire to secure by Letters Patent is:

1. In a time fuse the combination with a base member and a setting member mounted thereon adjustable to regulate the timing of 15 the fuse, said members having coaxial overlapping parts and one of them having a socket between said parts, of a wedge entering such socket and the inner and outer surfaces of which are convergent, said wedge 20 being normally held by said socket in place and in such loose engagement with said overlapping parts as to permit free adjustment of the setting member, but arranged to be forced upon firing by inertia tightly into 25 engagement with said parts, whereby to prevent displacement of the setting member.

2. In a time fuse the combination of a base member and a relatively adjustable setting member mounted thereon, said members 30 having coaxial and coextensive surfaces and an inserted annular locking piece contained partly in each of said surfaces, the base having also a socket, and a wedge entering said socket normally bearing loosely 35 at one side on the setting member and at the opposite side upon the opposite wall of the socket, and arranged to be forced by set back into locking engagement with said members whereby to prevent displacement of the setting member, and the setting member having 40 a shoulder overlying the wedge and at a distance from the mouth of the socket less than the length of the wedge when the members are assembled as described.

45. 3. In a time fuse the combination with a base of a setting member adjustable relatively thereto to regulate the timing of the fuse, a wedge located at a given point between adjacent parts of said base and said 50 member, being loosely engaged with the latter to permit adjustment thereof and adapted to be crowded by set back into tight engagement with said parts, and complementary means associated with said setting member and said wedge, respectively, arranged to limit the range of possible adjustment of the setting member.

4. In a mechanical time fuse a base, a setting member, and a combined wedge and 60 stop arranged to limit adjusting movements of the setting member at any time and to prevent all movements of said member after firing of a projectile equipped with the fuse from a gun.

65. 5. In a time fuse a base, a setting member

adjustable to regulate the timing of the fuse mounted on said base, a plurality of wedges inserted loosely between adjacent coaxial parts of said base and setting member angularly spaced about the axis of adjustment 70 of the setting member, a band connected to said wedges, and complementary stops on the band and setting member arranged to limit the range of possible adjustment of the latter.

6. In a time fuse, a base, a setting member mounted on the base and adjustable thereon about an axis to regulate the timing of the fuse, a band coaxial with said axis, a plurality of wedges projecting axially 80 from said band and adapted to be forced by inertia upon firing into locking engagement between adjacent parts of the base and setting member, said wedges and the base being complementally formed and arranged to permit of assemblage in only one position, and complementary stops on the band and setting member respectively arranged to limit the extent of adjustment of the member.

7. In a time fuse a base, a setting member mounted thereon and adjustable about an axis to regulate the timing of the fuse, a plurality of wedges and a connecting band arranged between contiguous parts of the 95 base and setting member coaxially with said axis, and the base having sockets to receive the ends of said wedges and compel placement thereof in a given relation, and complementary stops on the band and setting 100 member arranged to limit the adjustments of the latter.

8. In a time fuse the combination with a base of a rotatable timing device, a hammer and trigger mechanism releasable by said 105 timing device, a setting member adjustably mounted on said base with provision for rotating about the axis of rotation of said timing device, a disengageable coupling between said setting member and the timing 110 device for transmitting movement from the former to the latter, a wedge arranged in a given position between contiguous parts of the base and setting member adapted to be crowded by inertia between such parts when 115 fired from a gun, and complementary stops associated with said setting member and wedge arranged to prevent shifting of the timing device by the setting member into the position wherein release of the hammer 120 and trigger mechanism is effected.

9. In a time fuse the combination of a base, a plurality of wedges and a band forming a combined unit, said base having sockets into which the ends of said wedges 125 are adapted to enter, and an adjustable setting member rotatably mounted on the base surrounding said band and wedges, the outer sides of said wedges being substantially parallel with the line in which the 130

5 fuse is designed to move when fired from the gun and the inner sides of the wedges being inclined to such line and bearing against the adjacent sides of the sockets wherein they enter, whereby said wedges are forced by set back upon firing further into said sockets and are crowded outwardly to bind the setting member.

10. A combined locking and stop member comprising an annular band and projections extending from said band parallel to the axis thereof and spaced around such axis, the extremities of said projections being wedge shaped radially and a stop carried by said band.

11. In a time fuse the combination with a base, of an adjustable timing device, an adjustable setting member mounted on the base and engageable with said timing device for adjusting the latter, and a cap secured 20 to said setting member covering and completing the fuse, the rim of said cap overlapping the adjacent part of the setting member, and both the cap and setting member having interlocking shoulders preventing the removal of one from the other.

In testimony whereof I have affixed my signature.

OLOF OHLSON.
